UNITED STATES PATENT OFFICE.

GILBERT C. LANDIS, OF YORK, PENNSYLVANIA, ASSIGNOR TO AMERICAN PHOSPHORUS COMPANY, OF CAMDEN, NEW JERSEY, A CORPORATION OF NEW JERSEY.

ELECTRIC TERMINAL.

No. 922,917.

Specification of Letters Patent.

Patented May 25, 1909.

Application filed April 3, 1907. Serial No. 366,152.

To all whom it may concern:

Be it known that I, GILBERT C. LANDIS, a citizen of the United States, residing in York, Pennsylvania, have invented certain Improvements in Electric Terminals, of which the following is a specification.

The object of my invention is to so construct an electric terminal, that the carbon electrode can be readily and firmly attached to the terminal and which is so designed that it will be prevented from becoming overheated.

My invention is particularly adapted for use in connection with electric furnaces. In the accompanying drawings, Figure 1, is a vertical sectional view, illustrating my improved electric terminal with the carbon electrode attached; Fig. 2, is an inverted plan view of Fig. 1; Fig. 3, is a side view, showing 20 my improved terminal applied to an electric furnace, and Figs. 4 and 5, are views, showing modifications of the invention.

A is a carbon electrode, in the present instance, circular in cross section, as illustrated 25 in Fig. 2.

B is the terminal to which the electrode is attached. This terminal has a body portion B' and a cap C. The body portion has a cavity a in its under side of any depth desired for 30 the reception of the carbon electrode and the cavity is somewhat larger than the electrode so that when the carbon is placed in the electrode molten metal x of relatively low fusing point can be poured into the space between 35 the side walls of the cavity and the electrode so as to firmly secure the electrode to the terminal when the molten metal is set.

The body B' of the terminal is made in the form of a cup with a flange b' on its upper 40 edge and the central portion b², in which the electrode is mounted, projects up into the cup, as shown, and the cavity a is formed in this portion b². The cap C is secured to the body portion b by bolts e; a gasket E being 45 used when necessary so as to make a tight joint to prevent the escape of water.

i is a water inlet pipe and i' is a water outlet pipe. These water pipes i and i' are attached to the supply and waste pipes by 50 flexible connections so as not to interfere with the vertical adjustment of the electrode. Thus water is allowed to flow through the terminal and to fill the cup-like body portion B', keeping the wall of the portion b²

containing the electrode from becoming overheated.

Connection is made with the electric conductor through an arm b³, which preferably forms part of the body portion B' and secured to this arm is a plate F having an opening f for the conductor and this plate is secured to the arm by a bolt f' having a suitable nut f².

In the present instance, projecting from each side of the cap C are extensions c in 65 which are openings for the vertical guides C', illustrated in Fig. 3, and screwed into a boss c' on the cap is a screw eye or hook c² to which can be attached a rope or cord passing to a drum or counterbalance weight for vertically adjusting the electrode carried by the terminal in respect to the fixed electrode in the furnace.

The vertical guides in the present instance are tubes which are slipped over studs g projecting from the plate G supporting the gas seal G'. The upper ends of these tubular guides are secured to a beam C² in any suitable manner. By this means the terminal is held in proper position in respect to the body 70 of the electric furnace, as clearly illustrated in Fig. 3.

I have shown in Fig. 3, the upper portion of one form of electric furnace to which my invention can be applied, but it will be understood that my improved electric terminal can be used for any purpose without departing 75 from the essential features of my invention.

In Fig. 2, the carbon electrode is shown round and the terminal is circular, but in 80 some instances the electrodes may be square in cross section, then I prefer to make the terminal square to fit the electrode, as shown in Fig. 4, although the opening for the reception of the electrode may be quadrangular 85 and the other portions of the terminal may be of any shape desired.

In Fig. 5, I have shown a modification in which the end of the electrode A' is threaded, as at a', and this threaded portion is mounted within the cavity a of the terminal and metal in a molten state is poured around the threaded portion so as to retain the electrode in place.

When long electrodes are used I preferably 105 make them in sections; the threaded portion a' of one section extending in a threaded cavity a² in an adjoining section so that the

sections can be readily coupled one to another and when one is worn away another can be substituted for it. This construction is clearly illustrated in Fig. 3.

5. I claim:

1. The combination in an electric terminal, of a body portion having a cavity in its under side for the reception of an electrode, said body portion being in the form of a cup to 10 retain water, the part in which the electrode is held extending into the cup, with an inlet and an outlet conduit in the body portion for cooling liquid, said liquid surrounding the portion to which the electrode is attached, 15 with a cap closing the cup-shaped body portion and removable independently of said conduits, substantially as described.

2. The combination in an electric terminal, of a hollow body portion having its under 20 side extended inwardly to form a cavity, an electrode mounted in the cavity and secured to the body portion, circulating pipes communicating with the body portion, an integral arm projecting from the body portion; a terminal plate secured to the arm, and 25 a cap detachably secured to the body portion, substantially as described.

3. The combination in an electric terminal, of a flanged hollow body portion having a 30 cavity in its under side, a carbon electrode mounted in the cavity, and metal introduced between the electrode and the terminal while in a fluid state, water circulating pipes communicating with the interior of the body portion, a cap secured to the body portion hav- 35

ing means by which the terminal is suspended, with a terminal plate connected to the body portion independently of the cap, substantially as described.

4. The combination in an electric terminal, 40 of a hollow body portion having a cavity in its under side, a carbon electrode mounted in the recess, said recess being of greater diameter than the electrode, with soft metal introduced between the walls of the cavity 45 and the electrode, circulating pipes entering the body portion, a cap plate secured to the body portion of the terminal and having perforated extensions, guide rods passing through the extensions, an arm on the body 50 portion independent of the cap plate, and a terminal plate secured to the arm, substantially as described.

5. The combination of an electric furnace, 55 a plate mounted on the furnace having an opening for the passage of an electrode, studs projecting from the plate, vertical guide rods mounted on the studs a supporting structure engaging the upper ends of said rods, a terminal mounted on the rods, and an electrode 60 carried by the terminal, substantially as described.

In testimony whereof, I have signed my name to this specification, in the presence of two subscribing witnesses.

GILBERT C. LANDIS.
